A method of, and apparatus for, cleaning the spinning rotors of open-end spinning equipment, wherein the air flow through the spinning rotor upon the occurrence of a yarn rupture condition is reversed. Fibers are detached from the wall of the spinning rotor by virtue of the reverse flow of such air current, the fibers placed in a state of suspension and then removed, preferably by suction, from the spinning rotor.

METHOD AND APPARATUS FOR CLEANING THE SPINNING ROTORS OF OPEN-END SPINNING EQUIPMENT

BACKGROUND OF THE INVENTION

The present invention relates to a new and improved method of, and apparatus for, cleaning the spinning rotors or turbines of open-end spinning equipment.

During open-end rotor spinning processes individual fibers are delivered by an airstream to the fiber collecting surface or grooves of the spinning rotor or turbine. At that location the fibers are arranged in a manner well known in this particular art, deposited and spun into a yarn which can be withdrawn and wound in suitable form upon a yarn carrier.

The delivery of fibers must be interrupted as quickly as possible upon the occurrence of yarn rupture in order to prevent collecting an excessive quantity of fibers in the spinning rotor which, under these circumstances, can no longer be withdrawn. However, as a practical matter a rather large and uniformly distributed residual quantity of fibers deposit upon the fiber collecting surfaces of the spinning rotor which prior to again beginning the spinning operation must be removed. Although for most open-end spinning equipment presently used on an operational basis removal of the fibers is undertaken manually by opening the spinning rotor and suitably cleaning the fiber collecting surfaces, still several techniques have already become known in this art by means of which rotor cleaning is carried out automatically through the use of more or less suitable auxiliary means, such as brushes. Still the known techniques have the common drawback that in the long run it is impossible to achieve a complete removal of the fibers from the spinning rotor and, in particular, fibers which may possibly be located in the yarn withdrawal channel cannot be engaged and removed. In those instances it is only possible to again resort to cumbersome manual cleaning operations before the spinning operation can be again continued.

SUMMARY OF THE INVENTION

Accordingly, from what has been explained above it will be seen that a real need still exists in the art for techniques and apparatus for cleaning the spinning rotors of open-end spinning equipment in a manner not associated with the aforementioned drawbacks and limitations existing with the prior art techniques and apparatus constructions. Hence, a primary objective of the present invention is directed at cleaning such spinning rotors of open-end spinning equipment in a manner satisfactorily fulfilling the existing need in the art and not associated with the aforementioned drawbacks and limitations of the state-of-the-art techniques and apparatus constructions.

Yet a further significant object of the present invention relates to a novel method of, and apparatus for, effectively, reliably and efficiently cleaning the spinning rotors of open-end spinning equipment.

Now, in order to implement these and still further objects of the invention, which will become more readily apparent as the description proceeds, the method aspects of this development are manifested by the features that upon occurrence of yarn rupture the direction of flow of the air current through the spinning rotor is reversed, and by means of the reverse flow of the air current detaching the fibers from the wall of the

spinning rotor, placing such fibers in a suspended state and removing such fibers from the spinning rotor, preferably by suction.

Through the practice of the inventive method the complete engagement and removal of the fibers which remain upon interruption of the spinning operation is achieved in that, the spinning air current which originally also served to infeed or deliver the fibers is reversed in direction while maintaining as greatly as possible conformity in its flow path and consequently the transport of fibers is again, so to speak, "rearwardly rolled-up." By virtue of this procedure the most favorable conditions are provided for ensuring that all undesired fibers are again engaged, in other words that there is carried out a sufficient cleaning action, since the fibers have continuously been located at such flow paths and never externally thereof. Furthermore, this inventive method can significantly be practiced with as few as possible additional means or devices and, therefore, from the standpoint of economy, servicing and maintenance requirements is extremely advantageous.

As already indicated above the development of this invention is also concerned with a new and improved apparatus for the performance of the aforesaid method for cleaning the spinning rotors of open-end spinning equipment. The inventive apparatus comprises a spinning rotor having air throughpassage openings, the spinning rotor being arranged in a housing. There is also provided a fiber infeed or delivery channel as well as a yarn withdrawal tube or conduit. According to important aspects of this invention means are provided for the purpose of reversing the flow of air through the spinning rotor.

Now in accordance with a preferred physical manifestation of the present invention the flow through the spinning rotor is reversed, but with the same direction of rotor rotation. In this way the spinning rotor can be braked without requiring additional brake mechanisms. The kinetic energy of the rotating spinning rotor is thus reclaimed and employed for flushing and cleaning the fiber collecting surfaces. An additional expenditure of energy for obtaining a suction action, as such was the case for the previously discussed prior art techniques, is at most limited to taking-over the flushing flow which, so to speak, is delivered "free" by the spinning rotor and the removal thereof into a suitable collecting container or the direct uniting thereof with the spinning- and/or cooling air current present in any case at machines equipped with spinning rotor units. In the last-mentioned situation filtering-out the fiber material is undertaken centrally for each machine or in fact centrally for each group of machines.

BRIEF DESCRIPTION OF THE DRAWINGS

The invention will be better understood and objects other than those set forth above, will become apparent when consideration is given to the following detailed description thereof. Such description makes reference to the annexed drawings wherein:

FIG. 1 is a schematic illustration of a preferred constructional form of open-end spinning equipment using a spinning rotor;

FIG. 2 is a fragmentary sectional view taken through a spinning rotor with air conveying elements constructed as blades or buckets and with an associated blade regulating or adjustment mechanism;

FIG. 3 is a side view of a spinning rotor with its air conveying elements in the form of buckets, viewed substantially along the line III-III of FIG. 2;

FIG. 4 is a sectional view taken at right angles to the lengthwise axis of the spinning rotor of FIG. 2, with an arrangement of the blade structure for regulating the desired quantity of air flow;

FIG. 5 is an axial sectional view through a spinning rotor employing a second construction of air conveying elements; and

FIG. 6 is a sectional view taken perpendicular to the lengthwise axis of a spinning rotor having two groups of air throughpassage openings and employing a further construction of adjustment mechanism for the air conveying elements.

DETAILED DESCRIPTION OF THE PREFERRED EMBODIMENTS

Describing now the drawings, in FIG. 1 there is illustrated by way of example a preferred constructional form of inventive open-end spinning equipment comprising a housing 2 containing a spinning rotor or turbine 4, the spinning rotor 4 embodying a driven rotating rotor component 6 and a yarn removal or withdrawal component 8. The rotating rotor component 6 is supported by means of its shaft 10 in a bearing arrangement 12. Shaft 10 possesses a hollow construction and communicates in air flow relationship the interior 52 of the spinning rotor 10 via a support 14 with a suction conduit or line 16. A controllable slide valve unit 18 is arranged at the mouth of the support 14.

A fiber delivery or infeed conduit 20 piercingly extends through the housing 2 and serves to conduct the spinning fibers delivered from a suitable fiber separation mechanism 24 into the rotating component 6 of the spinning rotor 4. The separation mechanism 24, delivering the schematically depicted fiber arrangement or structure 26, embodies in known manner a delivery or feed cylinder 28 and an output or combing cylinder 30. The yarn 32 formed in the spinning rotor 4 is withdrawn from the yarn removal or withdrawal component 8 by means of withdrawal cylinders 34. The yarn 32 is then wound onto a spool 36 or the like.

Continuing, it will be understood that throughflow openings 38 are arranged at the rotor wall at a regular spacing from one another and at the same diameter of such rotor. The air freed of fibers can be removed from the interior 52 of the spinning rotor 4 by means of these throughflow openings 38. At the outlet side of the rotor 4 there are associated with such air throughflow opening 38 air conveying devices, here in the form of buckets or blades 40. In the arrangement of FIGS. 2 and 3 these blades or buckets 40 can be regulated by means of an adjustment mechanism 42 in such a manner that the conveying direction of the rotor 4 with the same direction of rotation can be reversed.

The course of the finished spun yarn 32 is monitored by a yarn feeler 44 which responds to eventual yarn ruptures. For instance, the yarn feeler 44 triggers an electrical signal which can be delivered by a line 46 to a suitable signal evaluation device 48. This evaluation device 48 is electrically connected on the one hand with the yarn separation mechanism 24 and, on the other hand, with the adjustment mechanism 42 for the rotor blades or buckets 40, and furthermore with the slide valve 18 of the suction line 16 — and as not illustrated — with a release or trigger mechanism for inter-

rupting the drive of the unit at which the yarn rupture has occurred, such as the drive 150 schematically depicted in FIG. 1.

The spinning rotor 4' illustrated in FIG. 2 will be seen to comprise a protruding annular or ring-shaped channel 50 which is separated from the interior compartment or internal space 52 of the rotor 4' by an air permeable yet not fiber permeable filter 54. This filter or sieve 54 possesses a fiber deposit trough 56.

10 Bores 38' distributively arranged at a regular spacing from one another over the entire periphery of the rotor 4' are provided at the base surface of the annular channel 50. A respective cage 60 is mounted in these bores 38', which cage is rotatable about an axis 62 parallel to

15 the rotor axis 64. Each cage 60 possesses a cylindrical component 66 which is mounted in the bore 38'. Two side flaps 68 which extend parallel to one another and in the direction of the axis 62 merge with the cylindrical component or portion 66, as shown.

20 A rotor blade 40' which can not only be simply curved as illustrated in FIGS. 2 and 3, rather also spatially curved, is pivotably mounted by means of a pin 70, the axis of which extends perpendicular to the rotational axis 62 of the associated rotor bucket or blade 40'. The pin 70 extends laterally from the rotor blade 25 40' and at the side facing the ring-shaped or annular channel 50 possesses a lengthwise extending notch or groove 72 in which there is fixed one end of a blade spring 74. The other end of this blade spring 74 is

30 guided in a protruding nose member 76 of one of the side flaps or walls 68, and wherein the spacing between nose member 76 and the notch 72 is chosen such that the blade spring 74 is slightly arched or domed, as shown. By means of the blade spring 74 the rotor blade 35 40', during each blade switching or reversing operation is forced into its terminal positions, respectively shown in solid and phantom lines in FIG. 3, and fixedly retained thereat.

40 A pin member 80 extends parallel to the axis of the pin 70 from the rotor blade 40' towards the outside in the direction of and at the region of a switching ring 82 displaceably mounted at the wall of the housing 2 containing the spinning rotor 4. The pin member 80 is not in contact with the switching ring 82 in both terminal

45 positions of such switching ring. The switching ring 82 is operatively connected in driving relationship, through the agency of a lever member 84, with a blade switching or reversing device 86 which is operatively connected via the evaluation device 48 with the yarn feeler 44.

50 By rotating the cages 60 containing the rotor blades or buckets 40' about the axes 62 it is possible to regulate the quantity of air which is to be conveyed through the spinning rotor 4. As best seen by referring to FIG. 4 with increasing angle α and rearwardly curved buckets or blades the conveyed air quantity for the rotor increases. If the angle α is adjusted so as to be negative at the other side (not shown), then, the conveyed air quantity for the rotor decreases.

55 60 During the spinning operation the fiber structure or arrangement 26 which is delivered to the separation mechanism 24 is broken up into individual fibers and by means of the fiber transport or conveying air is delivered through the fiber delivery or infeed conduit 20 to the rotor 4 or 4' respectively, spun together, and leaves in the form of a yarn 32 at the yarn withdrawal conduit or tube, then to be wound up at the spool 28.

Upon the occurrence of yarn rupture the yarn feeler 44 delivers a signal to the evaluation device 48 which causes the delivery of fiber to the separation mechanism 24 to be immediately interrupted and similarly ensures for the immediate interruption of the drive of the spinning rotor 4 or 4' respectively. At the same time the interior 52 of the rotor 4 or 4' respectively is operatively connected with the suction conduit or line 16 by opening the slide valve 18 and the blade switching ring 82 is displaced by the blade switching device 86 into the position depicted in phantom lines (FIG. 2) which, in turn, causes pivoting of the buckets or blades 40' into the position depicted in phantom lines in FIG. 3 through the agency of the pin member 80. Consequently, the rotor 4' with the same sense of rotation conveys air out of the housing 2 into its interior 52, in other words in the opposite direction than prevailed during the spinning operation.

The air flow through the rotor 4' now extends completely and in flow line conformity in the opposite direction from the direction prevailing during the prior spinning operation and thus detaches the fibers which are still lying in the fiber trough 56 from the rotor wall and places such detached fibers, together with the fibers which are still arriving via the fiber delivery conduit, into a state of suspension, so that these fibers can arrive through the agency of the hollow shaft 10 and the support 14 at the suction conduit or line 16 and at that location can be removed. Owing to the air conveying action in the opposite direction the rotor 4' is slowly braked and brought to standstill.

In order to obtain a more pronounced reverse flushing during the occurrence of a yarn rupture the possibility exists of briefly delaying release of the connection with the rotor drive and to initiate braking of the rotor only after having obtained the complete quantity of flushing air flow.

Prior to again placing the spinning rotor 4 or 4', respectively, into operation the buckets or blades 40' are again placed into their spinning position by means of the evaluation device 48 and the slide valve 18 is closed, so that the connection to the suction line or conduit 16 is interrupted.

Of course, it would be possible to achieve a reversal of the flow through the rotor also by changing the direction of rotation of the rotor after successfully braking same. To this end, there is schematically depicted in FIG. 1 a reversible drive motor 150.

The spinning rotor 90 illustrated in FIG. 5 is provided at its wall with bores 92 arranged at a regular or uniform spacing from one another at the same rotor diameter. Insert members 94 are rotatably mounted in these bores 92, the insert members 94 possessing inclined extending bores 96. The insert members 94 are coupled with one another by any suitable means in such a fashion that they can simultaneously rotate, and thus the bores 96 can change their position relative to the peripheral direction of the rotor. Depending upon whether the bores extend from the interior of the rotor 90 in the direction of rotation or opposite to the direction of rotation of such rotor 90, such will convey air out of the rotor interior towards the outside or in the reverse direction. By regulating the angle between the bores 96 and the corresponding peripheral direction, analogous to the discussion of the construction of FIG. 4, it is possible to adjust the air quantity which passes through the rotor 90.

Continuing, it is to be understood that in the wall of the spinning rotor 100 illustrated in the arrangement of FIG. 6, there are alternately arranged at regular spacing from one another at the same rotor diameter two groups of air throughpassage openings 102 and 104 respectively. The air throughpassage openings 102 are designed such that the spinning rotor 100 conveys air out of its interior towards the outside in the direction of rotation marked by the arrow, whereas the air throughpassage openings 104 are designed such that when such are effectual, air will be conveyed from the surrounding or ambient environment of the rotor 100 into its interior. The air throughpassage openings 104 are covered in the arrangement of FIG. 6 by a suitable closure member, such as the rotatable diaphragm or stop 106, so that they are ineffectual. The diaphragm 106 is operatively connected with a spring-loaded displacement mechanism 108 with which cooperates a centrifugal force lever 110. Upon the occurrence of yarn rupture and by means of the trigger mechanism 48 controlled by the yarn feeler 44 the connection to the drive of the rotor 100 is released. Consequently, the rotational speed of the rotor drops and the centrifugal force lever member 110 changes its position until it triggers the displacement mechanism 108. This displaces the diaphragm 106 in such a manner that the air throughpassage openings 104 are now effective and the air throughpassage openings 102 are closed, so that now air will be conveyed from the ambient or surrounding region of the rotor 100 into its interior. Consequently, the rotor will be further braked and finally brought to standstill. Upon again placing into operation the spinning rotor 100, the displacement mechanism 108 is again loaded by the starting torque or moment and the diaphragm 106 is displaced in such a way that the air throughpassage openings 102 are once again operable, so that the rotor 100 conveys air from its interior towards the outside and the spinning operation can be continued.

The removal of fibers following yarn rupture can also be carried out by the fiber delivery channel 20 or by means of the yarn withdrawal channel. During yarn withdrawal through the rotor shaft removal of the fibers during yarn rupture can also take place by a suction pipe or tube which is arranged "overhead."

While there is shown and described present preferred embodiments of the invention, it is to be distinctly understood that the invention is not limited thereto but may be otherwise variously embodied and practiced within the scope of the following claims. Accordingly,

What is claimed is:

1. A method for cleaning the spinning rotors of open-end spinning equipment, comprising the steps of reversing the air flow through the spinning rotor upon the occurrence of a yarn rupture condition, detaching fibers from the wall of the spinning rotor by virtue of the reverse flow of such air current, placing the fibers in a state of suspension and removing such suspended fibers from the spinning rotor.
2. The method as defined in claim 1, wherein the suspended fibers are removed from the spinning rotor by means of suction.
3. An apparatus for cleaning the spinning rotors of open-end spinning equipment, comprising a housing, a spinning rotor equipped with air throughpassage openings arranged within said housing, a fiber delivery channel for delivering fibers to the spinning rotor, yarn with-

drawal means for removing the spun yarn from the spinning rotor, and means for reversing the flow of air through the spinning rotor upon the occurrence of yarn rupture.

4. The apparatus as defined in claim 3, wherein said means for reversing the air flow through the spinning rotor comprises mechanism for reversing the direction of rotation of said spinning rotor.

5. The apparatus as defined in claim 3, wherein said means for reversing the air flow through the spinning rotor is adjustable and provided at said spinning rotor.

6. The apparatus as defined in claim 5, wherein said adjustable means comprises air conveying elements provided for the throughpassage openings for the air flowing through the wall of the spinning rotor.

7. The apparatus as defined in claim 6, wherein said air conveying elements comprise rotor blades.

8. The apparatus as defined in claim 6, further including insert members having bores, said air conveying elements being arranged at an inclination to the axis of the spinning rotor in said bores.

9. The apparatus as defined in claim 6, said adjustable means including an adjustment ring, said adjustment ring further including mechanism for fixing said adjustment ring in one of two terminal positions.

5 10. The apparatus as defined in claim 3, wherein said means for reversing the air flow comprises two groups of air throughpassage openings, and closure means for selectively blocking one group of said air throughpassage openings.

10 11. The apparatus as defined in claim 10, wherein said closure means comprises a diaphragm.

15 12. The apparatus as defined in claim 11, further including means for displacing said diaphragm, said diaphragm displacing means responding to centrifugal force and inertia forces during starting of the spinning rotor.

13. The apparatus as defined in claim 3, wherein said fiber delivery channel defines a suction channel for sucking-off the fibers.
